EYEGLASS FRAME

Harold N. Braunhut, 1812 Atlantic Ave., Brooklyn, N.Y.

Filed Jan. 4, 1961, Ser. No. 63,437

Term of patent 14 years

(Cl. D57—1)

The figure is a perspective view of an eyeglass frame showing my new design.

The rear not shown is plain and conventional.

The characteristic features of my design for the eyeglass frame disclosed reside in the lens-holding member attached to the top at the center of the frame as shown.

I claim:

The ornamental design for an eyeglass frame, substantially as shown and described.
